ELECTRIC LAMP

George Pupala, Mansfield, Ohio

Application October 22, 1931. Serial No. 570,288

6 Claims. (Cl. 176—26)

This invention relates to new and useful improvements in an electric lamp.

The invention has for an object the construction of an electric lamp which is characterized by the provision of a plurality of illuminating wires arranged in a fashion so that one or more may become fused while the remaining ones continue to burn and give illumination.

As another object of this invention it is proposed to construct the illuminating wires of different thickness or in groups of different thickness so as to eliminate the possibility of all of them burning out at the same time.

A still further object of this invention is to construct a lamp with a plurality of illuminating wires arranged over a short distance so as to reduce to a minimum breakage of the wires due to vibration.

As another object of this invention it is proposed to provide spare illuminating wires within the lamp and arranged so as to be movable into operative positions from the exterior of the lamp.

Furthermore, as another object of this invention it is proposed to construct a lamp with a plurality of radial arms, to arrange operative illuminating wires between certain of said arms, and to support spare illuminating wires upon the other of said arms, and provided with means capable of being magnetically acted upon from the exterior for bringing the spare illuminating wires into use.

A still further object of this invention is the construction of a safety lamp of the class described which is of simple, durable construction, dependable in use and efficient in action and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

45 In the accompanying drawing forming a material part of this disclosure:—

Fig. 1 is a schematic illustration of an electric lamp constructed according to this invention.

50 Fig. 2 is a schematic wiring diagram of the radial arms and illuminating wires of a modified form of electric lamp.

Fig. 3 is a fragmentary view similar to a portion of Fig. 1 but illustrating a modified arrangement.

Fig. 4 is a fragmentary enlarged detailed view of a portion of Fig. 3.

The safety electric lamp, according to this invention, comprises a vacuum bulb 10 supporting a contact shell 11 and an end contact 12. An upper and a lower group of spaced radial conductors 13 and 14 respectively are supported from a central stem portion 15 of the bulb 10. The lamp has a circuit which connects in series the contact end 12, the upper group of radial conductors 13, illuminating wires 16, the lower group of radial conductors 14 and the contact shell 11. This circuit is formed by a wire 17 which extends from the contact end 12 to the central common point of the radial arms 13 and a second wire 18, which extends from the contact shell 11 to the common central point of the radial arms 14.

The radial conductors 13 and 14 are of heavier material than the illuminating wires 16.

In Fig. 2 a modification of the invention has been disclosed in which the radial arms 13 and 14 are schematically shown so that the arrangement of the illuminating wires between them may be readily perceived. The illuminating wires are arranged vertically between the ends of the radial conductors indicated by reference numeral 16, and other illuminating wires 19 are arranged between the lower end of one of the illuminating wires 16 and the top end of the adjacent wires. Between each pair of the vertical illuminating wires 16 there is an inclined illuminating wire 19. It is well to state that during use of the lamp it is subject to vibrations which aid materially in shortening its life. For this reason, it is proposed to arrange the radial conductors 13 and 14 close together and still the necessary candle-power of the lamp may be obtained by reason of the ohmic summation of the illuminating wires. Furthermore, the wire 17 should be of different gauges for the purpose of preventing the possibility of their blowing at one time. Another advantage had by designing the wires 16 of different sizes is that they will burn out a number of hours apart from each other and in this manner give proper warning so that the lamp may be replaced before all of the wires burned out and the lamp is completely extinguished. A convenient arrangement of the lamp would be one in which alternate wires are of the same gauge and other wires of a different gauge.

In Figs. 3 and 4, another modification of the invention has been disclosed in which spare illuminating wires are provided which normally are not illuminated but can be moved into opera-

itive position magnetically from the exterior. The lamp is shown provided with a plurality of top radial conductors 13 and by the radial conductors 20 and 21 respectively. Illuminating wires 16 are permanently attached between certain of the conductors 13 and the conductors 20. Other idler illuminating wires 22 are permanently attached upon the remaining upper radial conductors 13 and at the bottom end are provided with catches 23 capable of engagement with the free ends of the radial arms 21. These catches are in the form of resilient plates having central openings 24 capable of engaging upon arrowheads 25 formed on the ends of the radial arms 21.

15 The plates 23 are of iron or similar metal which may be magnetically attracted from the exterior of the lamp so that the idler illuminating wires may be placed into use.

20 While I have shown and described the preferred embodiment of my invention, it is to be understood that I do not limit myself to the precise construction herein disclosed and the right is reserved to all changes and modifications coming within the scope of the invention as defined in 25 the appended claims.

Having thus described my invention, what I claim as new, and desire to secure by United States Letters Patent is:—

1. An electric lamp, comprising a vacuum bulb 30 supporting an end contact and a shell contact, a group of spaced upper and lower radial conductors within said bulb, means for supporting said conductors from said bulb, a circuit including in series said end contact, the upper of the group 35 of radial conductors, illuminating wire, the lower group of radial conductors, and said contact shell, spare illuminating wires depending from certain of said upper radial conductors, and catches on the free ends of said spare wires capable of co- 40 action with the free ends of certain of the lower radial conductors magnetically engageable from the exterior.

2. An electric lamp, comprising a vacuum bulb 45 supporting an end contact and a shell contact, a group of spaced upper and lower radial conductors within said bulb, and means for supporting said conductors from said bulb, a circuit including in series said end contact, the upper of the group 50 of radial conductors, illuminating wire, the lower group of radial conductors, and said contact shell, spare illuminating wires depending from certain of said upper radial conductors, remote 55 control operable catches on the free ends of said spare wires capable of co-action with the free ends of certain of the lower radial conductors.

3. An electric lamp, comprising a vacuum bulb 60 supporting an end contact and a shell contact, a group of spaced upper and lower radial conductors within said bulb, means for supporting said conductors from said bulb, a circuit including 65 in series said end contact, the upper of the group of radial conductors, illuminating wire, the

lower group of radial conductors, and said contact shell, spare illuminating wires depending from certain of said upper radial conductors, and magnetic operable catches on the free ends of said spare wires capable of co-action with the free ends of certain of the lower radial conductors controlled from the exterior. 80

4. An electric lamp, comprising a vacuum bulb 85 supporting an end contact and a shell contact, a group of spaced upper and lower radial conductors within said bulb, means for supporting said conductors from said bulb, a circuit including in series said end contact, the upper of the group of radial conductors, illuminating wire, the lower group of radial conductors, and said contact shell, spare illuminating wires depending from certain of said upper radial conductors, and catches on the free ends of said spare wires capable of co- 90 action with the free ends of certain of the lower radial conductors magnetically engageable from the exterior, said catches comprise a plate having a central opening, and an arrowhead on the lower radial conductors engageable in said central opening. 95

5. An electric lamp, comprising a vacuum bulb 100 supporting an end contact and a shell contact, a group of spaced upper and lower radial conductors within said bulb, means for supporting said conductors from said bulb, a circuit including in series said end contact, the upper of the group of radial conductors, illuminating wire, the lower group of radial conductors, and said contact shell, spare illuminating wires depending from certain of said upper radial conductors, and catches on the free ends of said spare wires capable of co- 105 action with the free ends of certain of the lower radial conductors magnetically engageable from the exterior, said catches comprise a plate having a central opening, and an arrowhead on the lower radial conductors engageable in said central opening, said plate being made of resilient material. 110

6. An electric lamp, comprising a vacuum bulb 115 supporting an end contact and a shell contact, a group of spaced upper and lower radial conductors within said bulb, means for supporting said conductors from said bulb, a circuit including in series said end contact, the upper of the group of radial conductors, illuminating wire, the lower group of radial conductors, and said contact shell, 120 spare illuminating wires depending from certain of said upper radial conductors, and catches on the free ends of said spare wires capable of co- 125 action with the free ends of certain of the lower radial conductors magnetically engageable from the exterior, said catches comprise a plate having a central opening, and an arrowhead on the lower radial conductors engageable in said central opening, said plate being made of resilient and magnetic material. 130
